UNITED STATES PATENT OFFICE.

CHARLES C. JACOBS, OF AMBOY, ILLINOIS, ASSIGNOR TO JACOBS STEEL EXCAVATOR COMPANY, OF AMBOY, ILLINOIS, A CORPORATION OF ILLINOIS.

EXCAVATING-MACHINE.

No. 829,214.

Specification of Letters Patent.

Patented Aug. 21, 1906.

Application filed January 2, 1906. Serial No. 294,202.

To all whom it may concern:

Be it known that I, CHARLES C. JACOBS, a citizen of the United States, residing at Amboy, in the county of Lee and State of Illinois, have invented certain new and useful Improvements in Excavating-Machines, of which the following is a specification.

This invention relates to excavating-machines of that general type wherein one or more buckets or scoops provided with a forward cutting edge is reciprocated across the ditch or trench to be dug by means of a chain or cable to which it is attached, said bucket or scoop being guided in its travel by a fixed guide having approximately the outline, form, or contour of the ditch or trench to be dug. A machine of this type is illustrated in Letters Patent No. 794,410, granted to me July 11, 1905, and my present invention is in the nature of an improvement upon machines of this type having for its object to increase the efficiency and control of the bucket during its operative or cutting movement. In the machine of the patent above referred to the bucket-operating cable is connected to the rear of the bucket in order to permit it to be automatically inverted on discharging, and the correct direction of movement of the bucket and of its cutting edge is determined by the guide. Experience has shown that such an arrangement imposes severe strains upon the guide, especially at the point where the bucket turns from the bottom horizontal wall of the trench to one of the inclined side walls on its cutting movement; and the object of the present invention is to provide a construction wherein the pull of the cable may be applied at the forward end of the bucket without interfering with the self-discharging capability of the bucket.

My invention will be readily understood when considered in connection with the accompanying drawings, wherein—

Figure 1 is an elevational view of a machine similar to that shown in my prior patent above referred to and having my present improvements embodied therein. Fig. 2 is an enlarged detail view of one end of the bucket-guide, showing the bucket-discharging means. Fig. 3 is a top plan view of the guide shown in Fig. 2. Fig. 4 is a cross-sectional view of the guide, showing the manner in which the bucket-carrier is mounted therein. Fig. 5 is a side elevational view of a

bucket-carrier and bucket equipped with my present improvements. Fig. 6 is a top plan view of Fig. 5; and Fig. 7 is a detail view in cross-section through a portion of the bucket-carrier frame, clearly illustrating the means for detachably connecting the forward end of the bucket-bail to the bucket-carrier.

Referring to the drawings and first briefly describing the principal parts of the machine in connection with which the present invention is shown, 5 designates as an entirety the main frame of the excavating-machine, the same being mounted on wheels 6, running on rails 7, whereby the machine is moved bodily along and over its field of operation. 8 designates as an entirety a guide in channel-track form mounted on and transversely of the main excavator-frame with capacity for vertical adjustment therein, said guide conforming to the outline contour of the ditch or trench to be dug and forming a rigid track, on which are mounted a series of rectangular trucks 9, carrying buckets or scoops 10. To the under side of the outer ends of the guide-track 8 are secured V-shaped frames 11, provided with supporting-tracks, on which the forward wheels of the truck-frames are adapted to run, said forward wheels entering the same through openings 12, Fig. 3, in the tracks of the main guide, for which purpose the forward truck-wheels are made narrower than the rear truck-wheels, as shown in Fig. 6. At each outer end of the guide is mounted a guide-pulley 13, over which is trained the bucket-operating cable 14. Preferably a pair of oppositely or inversely disposed buckets are employed, the adjacent rear axles of their respective trucks being connected by one or more links 15, Fig. 2. The machine as thus far described is substantially identical with the machine disclosed in the Letters Patent above referred to, to which reference may be had for a more complete description.

Considering now those features of improvement in which my present invention more particularly resides, 16 designates a forked bail that is mounted at its wide end on the pivot-bolt 17, by which the bucket is pivoted in its truck-frame. This bail, as shown in Figs. 5 and 6, is suitably curved or bent to normally overlie and extend forwardly of the upper forward edge of the bucket 10, herein repre-

sented by a transverse angle-bar 18, the ends of which latter, as shown in Fig. 6, overlie the upper edges of the side members of the truck-frame 9, whereby the depth to which 5 the lower forward cutting edge 19 of the bucket may penetrate the ground is limited, it being observed that the opposite upper side edges of the bucket are also preferably equipped with flange-plates 20, also overlying the side frame members for this purpose. The bail 16 extends forwardly of the upper forward edge of the bucket and is provided between its parallel side bars with a transverse catch 21, Fig. 7, that is adapted to 15 be engaged by the upper end of a hook 22, pivoted at 23 to the forward transverse member of the truck-frame. 24 designates a stop limiting the forward movement of the hook, the latter being allowed a limited backward swing sufficient to disengage it from the catch. The upper end of the hook is formed with an inclined edge 25 to facilitate the return engagement of the bail therewith after 20 having been disconnected therefrom. The 25 bucket-operating cable 14 is connected to the forward end of the bail 16 of each bucket, as shown.

In operation as the cable 14 draws the two buckets across the ditch along the guide 8 30 the forward or advance bucket takes a load of earth, the bail 16 occupying the position relative to the bucket shown in Fig. 5, wherein the hook 22 is engaged with the catch 21 during the travel of the operating- 35 bucket down one side of the ditch, across the bottom of the ditch, over the angle between the bottom and the other side. As the bucket makes this latter turn the engagement of the hook 22 with the catch 21 of the 40 bail causes the upward pull of the cable to be exerted directly on the forward end of the bucket-carrier, and thereby releases the guide-track of severe strain at this point, whereas where the cable is connected directly 45 to the pivot-bolt 17 or rear wall of the bucket the strain induced by the upward turning of the forward edge of the bucket under load was borne wholly by the guide-track. As soon as the bucket-carrier has passed in its 50 continued travel wholly onto the inclined side of the guide the hook 22 pulls back by gravity and releases the catch 21, thereby allowing the forward wheels of the bucket-truck to drop onto the discharge guide-track. 55 11 and the bucket to be inverted, the parts taking the positions shown in Fig. 2. On the return travel of the empty bucket as soon as

the bucket rides up the opposite inclined side of the guide the hook drops back by gravity again into engagement with the catch 21, and 60 the described operations are repeated. It will thus be seen that my present improvement provides means for relieving the guide-track of severe strain under the advance travel of the bucket from the horizontal to 65 the inclined part of its guide, while at the same time permitting the bucket to automatically upset and discharge its contents at the end of its travel.

I claim—

1. In an excavator of the class described, the combination with a bucket-carrier and a bucket pivotally mounted therein near its rear end, of a bail pivotally connected to the bucket near its rear end and overlying and 75 extending forwardly of the upper forward edge of the bucket, and means for detachably connecting the forward end of said bail to said bucket-carrier, substantially as and for the purpose described. 80

2. In an excavator of the class described, the combination with a bucket-carrier and a bucket pivotally mounted therein near its rear end, of a bail mounted on the bucket-pivot and overlying and extending forwardly 85 of the upper forward edge of the bucket, and a hook detachably connecting the forward end of said bail to said bucket-carrier, substantially as and for the purpose described.

3. In an excavator of the class described, 90 the combination with a guide, of a truck mounted to travel therein, a bucket pivotally mounted near its rear end in the frame of said truck, a bail pivotally connected to the bucket near its rear end and overlying and 95 extending forwardly of the upper forward edge of the bucket, and a pivoted hook detachably connecting the forward end of said bail to said truck-frame, substantially as and for the purpose described. 100

4. In an excavator of the class described, the combination with a guide, of a truck mounted to travel near its rear end in the frame of the truck, a bail mounted on the bucket-pivot and overlying and extending 105 forwardly of the upper forward edge of the bucket, a hook pivotally mounted on a member of said truck-frame, and a catch carried by said bail and engaged by said hook, substantially as and for the purpose described. 110

CHARLES C. JACOBS.
